SWITCH

Max Leroy Jeffrey, Shaker Heights, Ohio, assignor to The National Acme Company, Cleveland, Ohio, a corporation of Ohio

Application July 1, 1944, Serial No. 543,114

10 Claims. (Cl. 200—116)

1

This invention relates to switches and more particularly to a multi-pole switch having a quick make and break and also having provisions for opening the circuit upon an overload thereof.

One of the objects of my invention is to provide a switch of the multi-pole type where arcing is reduced to a minimum by a quick make and break mechanism.

Another object of my invention is to provide a switch wherein means is incorporated to cause the contacts to open when the circuit being controlled is overloaded.

Another object of my invention is to provide an improved overload releasing device.

Another object of my invention is to provide an improved thermostatically operated overload device.

Another object of my invention is to provide a switch which may be closed in an emergency in spite of the fact that the overload protection means has operated and the switch under such conditions is normally open.

Another object of my invention is to provide a switch mechanism capable of carrying high currents and yet wherein the space requirements for such a device are reduced to a minimum.

Another object of my invention is to provide a switch mechanism wherein the operating parts are enclosed in a water tight explosion proof housing.

Another object of my invention is to provide a switch which is adjusted for mounting in various positions, and which thus lends itself to mounting on and use with various types of mechanisms.

Other objects of the invention reside in economies in manufacture and the organization and arrangement of the parts such that adjustments, repairs and replacements may quickly and easily be made without the need of special tools or equipment.

Still other objects of the invention and the invention itself will become more apparent from the following description of an embodiment thereof and which description is illustrated by the accompanying drawings and forms a part of this specification.

In the drawings:

Fig. 1 is a top plan view of the exterior of the device;

Fig. 2 is an end elevational view thereof;

Fig. 3 is a plan view of the switch with the cover removed;

Fig. 4 is a vertical section taken on the line 4—4 of Fig. 3;

Fig. 4a is a similar view taken on the lines 4a—4a of Fig. 3;

Fig. 5 is a vertical section as indicated by the lines 5—5 of Fig. 3 through the housing for the switch, the interior mechanism being shown in side elevation;

2

Fig. 6 is a sectional view taken from a plane indicated by the lines 6—6 of Fig. 5;

Fig. 7 is a top plan view of the contactor drum assembly removed from the switch;

Fig. 8 is a side elevational view thereof;

Fig. 9 is an end elevational view thereof taken from a plane indicated by the line 9—9 of Fig. 8;

Fig. 10 is a section taken on the line 10—10 of Fig. 8;

Fig. 11 is a fragmentary view, through the center of the switch with certain parts shown in elevation and with other parts broken away and shown in section, and particularly illustrates the clutch mechanism and its manner of connecting the snap mechanism to the contactor drum as well as the overload releasing thermostat;

Fig. 12 is a vertical section taken from a plane indicated by the line 12—12 of Fig. 11;

Fig. 13 is a rear elevational view of the snap mechanism housing assembly;

Fig. 14 is a side elevational view of one of the clutch levers;

Fig. 15 is a front view thereof;

Fig. 16 is a side elevational view of a clutch lever which cooperates with that of Fig. 14;

Fig. 17 is a rear view thereof;

Fig. 18 is a view of the contactor drum operating lever taken from the side which is disposed adjacent the end of the contactor drum;

Fig. 19 is an opposite face view thereof with a portion broken away and shown in section;

Fig. 20 is a top plan view thereof;

Fig. 21 is a side elevational view thereof;

Fig. 22 is a side elevational view of the thermostat element removed from the device;

Fig. 23 is a front view thereof;

Fig. 24 is a developed view of the thermostat heater element assembly;

Fig. 25 is an end elevational view of one of the heating elements;

Fig. 26 is a circuit diagram showing one manner in which connections to the device for controlling a three-phase circuit may be made;

Fig. 27 is an end view of the contactor drum supporting bracket;

Fig. 28 is an exploded view of the heater element assembly; and

Fig. 29 is a side elevational view of one of the fixed contact carrying blocks, removed from the assembly.

Referring now to the drawings throughout which like parts have been designated by like reference characters, and first particularly to Figs. 1 and 2, I have illustrated a housing which 55 comprises a base housing 10 and a cover housing 11. The base comprises a substantially rectangular bottom portion 12 which is provided with openings 13 through which studs may extend and by means of which it may be mounted as desired. The housing 10 is provided with walls which rise from the bottom portion spaced

from the ends and is contoured to receive the mechanism hereinafter described. The end walls of the housing are formed to provide internally threaded hollow bosses 14 which provide for coupling to a conduit pipe not shown and through which connecting wires, omitted in the interest of clarity of description, may extend for connection to the switch terminals. The upper portion of the base housing terminates in a flange 16 the upper surface of which is ground flat and adapted to receive the cover 11. The cover 11 is likewise provided with a lower flange 17 having a face corresponding with that of the flange 16. Screws 18 extend through openings in the cover flange 17 and into threaded openings in the flange 16 for holding the cover seated on the base. The faces of the flanges 16 and 17 provide a close fit rendering the same substantially fluid tight and in addition thereto the inner wall of the cover, as can best be seen in Fig. 6, is displaced inwardly relative to the inner wall of the base and a groove 19 is provided in the flange 17 which groove is spaced from the edges of the flange and overhangs the wall of the lower housing. A gasket 20 of rubber or similar material is disposed in this groove and when the cover is placed on the base this gasket is compressed by the upper inner edge of the lower housing to provide a further effective seal. The upper and lower housing parts are thus effectively sealed to each other in fluid, gas and air tight engagement.

The cover besides acting as a cover for the lower housing, also supports the main operating lever 25 which, as best shown in Figs. 1, 2 and 5, includes a central boss having a bore 26 enabling it to be secured to a shaft 27 and pinned thereto by a taper pin 28. Extending laterally at diametrically opposite sides from the central boss are portions 29 provided with finger engaging seats which enables the shaft to be rocked by simply pressing down on one end or the other of the lever.

The shaft 27 extends through a bore in the boss 30 in the end of the cover, having a close sliding fit therewith, and is provided on its inner end with a cylindrical enlargement 31 which is transversely slotted adapted for engagement with the snap switch operating mechanism. The end 31 fits in an enlarged counterbore 32 and a packing 33 is disposed between the shoulder provided by the cylindrical end and the shaft and the end of the bore. On the outside of the housing and surrounding the bore which receives the shaft 27, there is provided an annular groove 34 which opens toward the enlarged boss 36 on the lever 25. A helical spring 37 is disposed in the groove being seated in the bottom of the groove and resiliently pressing against the lever 25, pushing the lever outward and holding the inner part 31 in effective sealing engagement with the gasket or packing 33.

An emergency clutch operating pin 40 extends from the rear of the raised portion 41 of the cover, which raised portion is provided to house the snap switch operating mechanism and the thermostat control. This raised portion is provided with a vertically extending wall 42, at the rear, that has a boss 43 in its upper part. The boss is provided with a bore 44 for slidably receiving the stem 45 of the pin 40. A counterbore 46 is provided around the stem and houses a helical spring 47 that has one end seated against the end of the bore and the other end in engagement with the inner end of the head of the pin

48 which head extends beyond the confines of the housing. The other end of the lever extends inside the housing and is provided with an inner head 48 riveted to the end of the stem. A packing washer 49 is provided between the inner head 48 and the end wall of the housing. The spring 47 normally urges the lever in an outward direction with the packing washer in sealing engagement with the inner head and end wall.

It will thus be seen that provision is made for effectively sealing all operating levers extending into or out of the housing as well as the housing itself to assure an effective seal against the admission of gases, liquids or the like, and prevents accidental ignition of volatile gas by sparking of the contacts during operation of the device.

Generally speaking the switch mechanism in the housing constitutes a rotary drum which carries the switch contacts. This drum is spring biased to normally hold the contacts in open circuit position. A snap action mechanism is provided for quickly rotating the drum and its contacts, and a clutch mechanism connects the snap mechanism to the contact drum. A thermostat is provided for disengaging the clutch should the circuit under control become overloaded.

The snap action mechanism in many respects is similar to that disclosed in my Patent No. 2,294,559 of September 1, 1942. It comprises a housing 50 the formation of which can be best seen in Figs. 6 and 13, the forward side of which is closed by a plate 51 held onto the face of the housing by screws 52 which extend through the plate into bosses 53 formed in the housing side walls. A pair of laterally extending lugs 54 are provided on the side walls near the lower end of the housing, the lugs being strengthened by webs 55 slanting upward as best viewed in Fig. 6, and the snap mechanism housing is supported in the lower housing 10 by these lugs which are seated on bosses 56 formed integral with the sides and bottom of the housing 10. Screws 57 extend through holes in the lugs and are threaded into the bosses 56. The mechanism is thus supported in an upright position in the housing and extends vertically upward to a point spaced from the underside of the cover.

A lever 60 is pivotally journalled in the upper apex of the housing 50 being secured on a shaft 61 by a tapered pin 62. The shaft in turn has the one end journalled in the rear wall of the housing 50 (Fig. 13) and the other end is provided with an enlarged circular head 63 which is journalled in an opening in the cover plate 51 and is provided with a substantially rectangular lug 64 which extends transversely across the head 63 and protrudes forward from the cover plate. This lug is adapted to be interlocked with the slotted head 31 of the manually operated shaft 27. Driving connection is thus effected from the lever 25 thru the shaft 27, head 31 and lug 64 to the shaft 61; and the lever 60 may thus be swung by moving the lever 25. A rock lever 66 is provided, being carried on a shaft 67 and locked thereto by a taper pin 68. The shaft 67 is journalled in a bearing 69 in the rear housing wall and the other end of the shaft is journalled in a bearing 70 in the cover 51, as can best be seen in Fig. 11. The end of the shaft 67 extends through the rear end of the housing and has integral therewith a part of the clutch mechanism hereinafter more fully described.

As best shown in Fig. 6 the lever 60 is provided with a roller 72 carried by a slide 73 which roller is held in spring pressed engagement with the face 74 of the rocker 66 by a spring 75 disposed in a bore in the lever 60. The rocker is adapted to be rocked by the lever 60 when it is swung from one side of the housing to the other. Movement of the rocker is restrained by a pair of pawls 77 journalled on pins 78 disposed spaced from and below the rocker axis at opposite sides of the housing. These pawls are held in spring pressed engagement with the opposite ends of the rocker by spring 79 each of which is disposed over a pin 80 riveted in the side wall of the housing with the other end seated in a recess 81 in the pawl. Each pawl on the sides facing toward the rocker is provided with two rocker engaging stops 82 and 83. The stop 82 limits the movement of the rocker after it is released from the stop 83 and the stop 83 holds the rocker against movement until the side of the lever 60 engages the lug 84 which is disposed on the end of the pawl. The operation is the same as described in the aforesaid patent; that is, when the lever is rocked from the position shown in Fig. 6 to the opposite side, the roller rolls up the inclined face of the rocker. The roller 72 and its supporting slide are forced upward in the lever, compressing the spring 75. The spring pressure increases and the roller presses harder against the rocker as it travels upward over the roller. The rocker in the meantime is held against rocking since the end of the rocker is in engagement with the stop or shoulder 83 on the pawl 77. As the roller approaches the end of the rocker it slides up on the raised portion 85 of the rocker, which causes still greater pressure to be exerted at which time the side of the lever 60 hits the projecting portion or lug 84 of the pawl rotating the pawl against the pressure of the spring 79 and withdrawing the stop 83 from under the end of the rocker. The spring pressed roller then snaps the rocker (in this instance clockwise from the position shown) downward onto the shoulder 82 of the pawl. The movement of the rocker is therefor a quick rotational movement. That is, it is snapped into position. The other pawl then engages the other end of the rocker where it holds it until the lever 60 is moved to the position shown. The movement of the pawls away from the rocker is limited by abutments 87 integral with the sides of the housing.

As previously stated the shaft 67 extends through the bearing 69 in the back wall of the snap mechanism housing and is provided on the rear with one part of the clutch mechanism. As best shown in Figs. 11 and 13 this element constitutes a cup which has a circular body 90 provided with a peripheral flange 91, and a coaxial stem or stub shaft 92 which extends in alignment with the shaft 67. This shaft provides a support for the clutch parts as well as supporting one end of the rotatable contact carrying drum 93 (Figs. 7 and 8), the other end of the drum being supported in a bearing 137a in a bracket 154 (Fig. 27).

The end of the drum adjacent the clutch is provided with a pair of lugs 95, Figs. 7 and 8, disposed diametrically opposite each other and adapted to engage in recesses 96 in a driven clutch member 97, Figs. 18 to 21, incl.

The driven clutch member includes a circular body having a peripheral flange 98; a central opening 99 being provided through which the stem 92 on the cup body 90 of the other clutch

member extends, the driven clutch member being thus supported and the flanges 91 and 98 on the two bodies extending toward each other to provide a chamber or recess therebetween, Fig. 11. The driving clutch flange 91 is provided with a slot 100 and the driven clutch member likewise with a slot 100a, which slots are normally in alignment with each other and provide a space through which the tongues 101 and 102 of intermediate clutch levers 103 and 104 may extend. The driven clutch member 97 is provided with a downwardly extending lug 105 which has a socket 106 formed therein, as best shown in Fig. 15. This socket receives one end of a spring 107 (Fig. 12) the other end of which is adjustably carried by a screw support 108 extended in the wall of the fixed contact carrying support 109 and which may be locked in any desired adjusted position by a lock nut 110. The spring 107 tends to rotate the drum 93, through the member 97 in a direction to normally open the contacts. A stop, which comprises a screw member 111 having a projection 112 for engagement with the lug 105 is provided, being screw-threaded through the opposite fixed contact carrying member wall 114. The stop may be locked in any desired position by the lock nut 113. This stop limits the amount of movement of the member 97 and hence the drum 93. It will be apparent from the foregoing that the driving and driven clutch members are supported in juxtaposed positions to each other. The driving connection therebetween is effected by the intermediate members 103 and 104.

The intermediate clutch member 103 includes a circular body of slightly less diameter than that of the recess formed by the flanges 91 and 98 of the driving and driven clutch members and is provided with a central opening 116 which tapers outwardly at 117. The member is disposed on the stem 92 in the recess between the driving and driven clutch members and because of the tapered opening may tilt therein as can best be seen in Fig. 11. The tongue 101 of the member 103, as previously stated, extends upward through the openings 100—100a in the flanges 91—98. The driven clutch member 97 is provided with an aperture 118 which extends through the wall, spaced from the edge and opposite the opening 100a. The drum 93 is provided with a recess 119 in alignment with the aperture 118 and a spring 120 is disposed in the recess and extends out through the aperture 118 and into engagement with the tongue 101 of the member 103 and causes the intermediate clutch lever to be tilted on the stub shaft 92 as shown in Fig. 11. The tongue 101 is bent slightly at 121 and extends upward opposite the end 122 of the thermostat element 123, the bend 121 permits the tongue to be in parallelism with the thermostat even though the intermediate clutch member is tilted.

The other intermediate clutch member 104 constitutes a circular body which is thinner than the other intermediate clutch member 103. It is also provided with the central opening 125 which is large enough to allow this member also to be tilted, it being supported in like manner on the stem 92 in the recess formed by the driving and driven members. The lower end of the body is provided with a lug 126 which extends toward and is adapted to be in engagement with the body of the member 103. This lug acts as a fulcrum or pivot for the member as will hereinafter more clearly appear. The stem 102 also

extends upward from the body of this member 104, through the slots 100—100a in the driving and driven clutch member flanges. The stem is provided with a lug 127 which extends toward the other member 103 and is adapted to seat against the stem 101 of the other member. Above the lug 127 the stem is bent outward at 128 in a substantially S-shaped curve and terminates in a straight upstanding portion 129 opposite to the other end member or leg 130 of the thermostat element 123. The cup member 80 is provided with a recess 131 that carries a spring 132 which bears against the intermediate member 104 tilting it on the stem 92 in a like manner as described for the other intermediate member. Thus the two clutch members are held in engagement with each other. The member 103, because of the thicker body, and the member 104 because of the lug 127, cross the meeting edges of the flanges of the driving or driven members between the flanges 81—88.

It will thus be seen that in the position shown the drive from the driving member 80 to the driven member 81 is effected by the tongues 101—102 of the intermediate clutch members 103—104 at the openings 100—100a in the flanges of the driving or driven members. As long as the intermediate members remain tilted, as shown in Fig. 11, the drive connection will remain intact, that is, the lug 127 will be across the junction of the flanges 81—88. However, if an overload should occur, the operating legs 122 and 130 of the thermostatic member, which is bi-metallic in character, will move apart. The leg 130 will engage the tongue 102 at 128 and the leg 122 will engage the tongue 101 and the two intermediate clutch members 103—104 will be moved from their tilted position to a vertical position, the lug 126 on the member 104 acting as a fulcrum, and against the pressure of the springs 120—132. In this position the tongues on the intermediate members are no longer opposite the junction of the flanges 81—88 but are well within the confines of the respective slots 100 and 100a and the driving and driven members are free to operate independently. This action occurs when the switch contacts are in a closed position, this being the position shown in Fig. 12 where the spring 107 is compressing and exerting pressure against the lug 105 of the driven member 81. The current is utilized during overload to heat the thermostat 123, the clutch is released and the spring 107 rotates the drum 93 with its contacts to open position as will be more fully described hereinafter.

It will thus be seen that a drive is effected from this snap mechanism to the contact carrying drum 93. This drum, as best shown in Figs. 7 to 10, inclusive, comprises a cylindrical body of insulating material having the lugs 95 on one end and each end provided with axial bores or recesses 135 and 136. The drum is supported at one end by the stem 92 and at the other end by a pivot pin 137 which is journalled in the opening 137a of the bracket 154.

The drum is provided with three transverse openings or channels 138 of rectangular cross section. In each channel there is disposed a contact carrying member 139. The members 138 are flat metal strips of sufficient length to extend the desired distance beyond the periphery of the drum, and carry on their ends contacts 140. It will be noted that the contacts, which are riveted in openings near the end of the strip are on opposite faces of the strip. The center of each strip

has an opening 141 therein and a pivot pin 142 extends through the opening and provides a support for the contact. The pin 142 extends transversely across the opening 138 and the ends of the pin are provided with heads 143 which engage the bottom of the counterbores 144 in the drum. Also journalled on the pins 142 and in engagement with the side wall of the opening are plates or strips 145 each of which has a lug 146 which extends normal to the body of the strip and is adapted to engage the contact carrying strip intermediate its ends and the pivot to provide a fixed stop therefore. The contact carrying strip is held against these stops by springs 147 disposed on a lug on the strip and the other ends of which surround pins on the body of the contact strip. The openings 141 are large enough so that the strip may tilt freely on its pivot. Normally the contacts are held in the position shown in Fig. 10 but when contact is made the strip may rotate or pivot from the position shown against the pressure of the springs 147. Hence, it will be seen that the drum and contacts are capable of movement relative to each other and that the drum may rotate a certain amount after contact is made. Although I have shown 3 sets of contacts it will be obvious that the number of sets may be increased or decreased without departing from the invention.

30 The contact carrying drum is rotatable between a pair of blocks each of which carries fixed contacts. These are best shown in Figs. 3, 4 and 4a. Each block comprises a member 150 constructed of suitable insulating material of generally rectangular cross section, and which is provided with circumferentially extending ribs 151 between which are disposed the contact carrying portions 152. The blocks are supported above the bottom of the lower housing 10 upon bosses integral with the lower housing. The rear end boss is indicated at 153 and carries a bracket 154, Fig. 27, which is secured to the top of the boss by a screw 155 which extends through an ear 156 on the bracket into the boss. The blocks are in turn secured to the bracket by screws 157. The front ends of the blocks are supported by the long bolts 158 (Fig. 5) which extend through the lower end of the snap mechanism housing and bolts 158a directly above as can be seen in Fig. 12.

50 The contact carrying parts of the blocks have secured thereto general U-shaped contact strips 161 which are held thereon by screws 162 that extend through the strips and are threaded into bushings 163 molded into the blocks (Fig. 4). The upper end of each strip, which extends horizontally across the block, is provided with a connecting screw 164 by means of which conductors may be secured in electrical connection to each strip. The end of the strip in the left hand block (Fig. 4) extends beyond the screw 164 and terminates in an upwardly extending extremity 165 which carries the fixed contact 166. These contacts are so disposed as to make connection with the contacts 140 when the contacts 140 are rotated thereagainst.

60 The block on the other side is substantially the same as the other except that the contact carrying strip in this case extends downward at its lower extremity and carries contacts to connect with the contacts on the other end of member 138.

65 In Fig. 4a the right hand contact carrying strip is shown as two separate strips with a rib 167 therebetween. In this case the upper strip 168 is L-shaped and carries no contacts and merely serves as a junction block, while the lower

strip is also L-shaped and carries the lower contact 166a'.

The inner faces of the block are provided with semi-circular channels 169 to provide clearance space for the rotatable drum. The drum with its contacts is rotatable between the blocks.

In operation if pressure is exerted on the right hand handle 29 as viewed in Fig. 2, to move it to the position shown, it causes the lever 60 in the snap mechanism to swing to the left (Fig. 6) which rotates the rocker 68 counterclockwise. This motion is communicated through the clutch to the contact carrying drum which causes the rotatable contacts to engage with the fixed contacts completing the circuit. In this position, with the contacts closed the spring 107 is compressed exerting pressure against the arm 105 of the clutch member 97, which pressure, were it not for the clutch mechanism, would open the contacts.

When it is desired to open the circuit the left hand end of the lever 25 is rotated and the contact drum is rotated to the open position.

As previously mentioned means is provided to open the circuit automatically should an overload in the electric circuit occur. This is accomplished by causing the current through the circuit to heat a thermostat unit which disengages the clutch between the driving and driven members after which the spring 107 rotates the drum with the contacts to open position. After the thermostat cools off the circuit may again be closed by rotating the lever 25 first to the "off" position, where the clutch elements are interlocked, and then to the "on" position. Means is also provided in case of emergency so that the contacts can be closed in spite of the overload if desired.

As previously briefly described, the tongues 101-102 of the intermediate clutch elements are adapted to be engaged by the ends 122 and 130 of the thermostat to force the clutch elements apart and disengage the clutch.

The thermostat element is supported by a pair of brackets 171 secured to the top of the snap housing 50 by screws 172. These brackets constitute arms which extend rearward and slightly upward from the housing. The thermostat element per se comprises a pair of bi-metallic strips 173 and 174 bent into circular form as best shown in Fig. 22, the strip 173 being disposed inside of and spaced from the strip 174. Interposed between the two thermostatic elements are heating elements 175 and are provided with connectors 176 at the ends. A U-shaped bracket 177 is soldered or welded to the top of the element, being provided with ears 178 which are engaged by screw 179 which extend through the brackets 171 into the ears and thus support the same above the clutch tongues with the ends 122 and 130 extending downward between the tongues 101-102. In the embodiment shown the end 130 is a separate element welded to the end of the outside thermostat strip 174. The element could all be made in one piece if desired.

A developed view of the heater element is shown in Fig. 24 and it comprises three wide mica strips 181 between which is sandwiched a thin narrow mica strip 182 around which resistance material 183 is wound. The ends of the resistance ribbon may be spot welded to metal connection strips 186 and these in turn have the connectors 176 secured thereto. The strip 182 is held by the connector 186 one end of which is carried around the strip to clamp it.

In this manner the resistance wire is held

against uncoiling from around its support and a stable connection for the wires 176 is afforded. The entire resistance element is held assembled by eyelets 184 which extend through all these elements as best shown in Fig. 24.

After the heater element is assembled between the two thermostat or bi-metallic elements, the entire assembly is held together by an eyelet or rivet 187 which is inserted through openings intermediate the eyelets 184.

One manner of connecting the switch is shown in Fig. 26 although the invention is not by any means limited to the precise manner shown which is merely for the purpose of explanation and not intended as a limitation upon the invention. Here it is desired to connect a three-phase circuit to a motor. The current is taken from the three-phase power line 200 to the lower contacts 166 the circuits being designated as L1, L2 and 20 L3, through the movable contacts 140 and strips 139 to the upper contacts 166a and 166a'; these circuits being designated as M1, M2 and M3. The circuit from M2 leads directly to the motor. The circuit M1 however is connected in series with the 25 H2 which corresponds to the resistance element 183. In this instance two separate heating elements are included in the circuit. From H2 the circuit extends back to the junction block 168 and thence to the motor. The other leg of the 30 circuit is from H3 through the resistance element back to the junction block 168' and thence to the motor. It will therefore be noticed that each of the phase windings of the motor is through a heater element. Fig. 28 is an exploded view of a 35 heater element adapted for use in a circuit such as described. Here there is illustrated the resistance or heater elements 182 which are sandwiched between the mica strips 181. In this instance as indicated in Fig. 26, there are two heater 40 elements, although only one heater element might be desirable in certain instances as where a single phase circuit is being controlled.

Upon a predetermined overload in any part of the circuit, either one or both of the heating elements will, with an increase in current, heat the bi-metallic strips 173-174 causing them to expand differentially and move the ends 122-130 apart. This causes the release of the clutch and the opening of the circuit as previously explained.

Normally it takes some time for the thermostat unit to cool off. In some instances it may be desirable or necessary to close the circuit in spite of the fact that the overload is so recent that the bi-metallic strips have not returned to their 55 normal position.

This may be effected through the emergency operating button 40. The button 40 may be pressed inward against the pressure of the spring 47 until the head 48 engages the end 190 of a lever 191, Figs. 5, 11 and 12. The lever 191, as can best be seen from Figs. 11-12, comprises a substantially flat member of generally rectangular formation supported between the brackets 171 by projections 192 which are pivotally journaled in 60 holes in the brackets opposite to each other spaced from and behind the snap mechanism housing and between that housing and the thermostat. The lower end of the lever 191 extends forward at 193 in a position adapted for engagement with the tongue 129 on the intermediate clutch element 104. The upper end of the lever 65 extends toward and into alignment with the head 48 on the emergency pin 40.

When the pin 40 is pushed in the head 48 engages the upper end 190 of the lever 191 and fur-

ther movement of the pin rotates the lever about the pivots 192 and then forces the lower end into engagement with the tongue 128 and moves the intermediate clutch lever, which is being held in a vertical position by the thermostat, to the position shown in Fig. 11. Just previous to effecting this action the snap mechanism has been moved to the "off" position so that the openings 100—100a in the flanges of the clutch members are in alignment. This permits the tongue to 10 again effect engagement of the clutch as long as the pin 40 is held in place in spite of the fact that the thermostat is attempting to release it. The flexibility of the thermostat element and the fact that it is pivotally supported at 178 permits it to be moved without damaging it. After the member 104 is moved back to its normal position the snap mechanism may again be operated and the circuit will again be remade and will stay remade as long as the operator maintains pressure on the head 40 of the emergency pin.

It will be noted by reference to Fig. 12 that the thermostat element 123 is relatively wide, as is also the release lever 191 to insure alignment with the ends 101 and 128 of members 103 and 104 through the ranges of rotation of the elements.

It will thus be seen that I have provided a switch mechanism which is compact, utilizing but 30 a small space and capable of being mounted in many positions. Furthermore, the manner of housing the parts is such that it eliminates the hazards of fire and explosion due to arcing inasmuch as no parts are open or exposed.

Furthermore it provides a switch that affords an exceedingly quick make or break thus decreasing the tendency for the contacts to arc with consequent burning of the points regardless of the manner in which the control lever is operated. It has also been shown how the switch automatically opens upon overload and cannot be accidentally reclosed. Also it has been shown how in case of emergency the switch may be operated in spite of the fact that the circuit is overloaded, should it be desirable or necessary. The construction is such that heavy currents may be handled without the necessity of a large and cumbersome mechanism. The device is also accessible for quick and easy replacement of worn or broken parts.

Having thus described my invention I am aware that numerous and extensive departures may be made therefrom without departing from the spirit or scope of the invention.

I claim:

1. A circuit controller including a stationary contact holder and stationary contacts thereon, a movable contact holder having movable contacts for engaging the fixed contacts to complete a circuit therethrough, means biasing said movable contacts to open position, means for controlling said movable contact holder including a snap action mechanism and a clutch connecting the snap action mechanism to the movable contact holder, means for connection in the circuit to be controlled responsive to overloads in said circuit and connected to said clutch to disengage said clutch, said biasing means adapted to move said movable contacts to open position upon disengagement of the clutch.

2. A circuit controller including a stationary contact holder and stationary contacts thereon, a movable contact holder having movable contacts for engaging the fixed contacts to complete

5 a circuit therethrough, spring means biasing said movable contacts to open position, means for moving said movable contact holder including a snap action mechanism and a clutch connecting the snap action mechanism to the movable contact holder, means for connection in the circuit to be controlled, responsive to overloads in said circuit and connected to said clutch to disengage said clutch, said spring biasing means adapted to move said movable contacts to open position upon disengagement of the clutch.

3. A circuit controller including a stationary contact holder and stationary contacts thereon, a movable contact holder having movable contacts for engaging the fixed contacts to complete a circuit therethrough, spring means biasing said movable contacts to open position, means for moving said movable contact holder including a snap action mechanism and a clutch connecting the snap action mechanism to the movable contact holder, means for connection in the circuit to be controlled responsive to overloads in said circuit and connected to said clutch to disengage said clutch, said spring biasing means adapted to move said movable contacts to open position upon disengagement of the clutch, and means to overcome said overload responsive means and permit re-engagement of said clutch and closing of said circuit.

4. A circuit controller including a stationary contact holder and stationary contacts thereon, a movable contact holder having movable contacts for engaging the fixed contacts to complete a circuit therethrough, spring means biasing said movable contacts toward open contact position, means for moving said movable contact holder including a snap action mechanism and a clutch for connecting the snap action mechanism to the movable contact holder, means for connection in the circuit to be controlled, responsive to overloads in said circuit and connected to said clutch to disengage said clutch upon overload, said spring bias adapted to move said movable contacts to open position upon disengagement of the clutch, and means to overcome said overload responsive means and permit re-engagement of said clutch and closing said circuit comprising a manually operated lever having a part disposed for engagement with the clutch.

5. An apparatus of the class described including a housing, an opening in one end of the housing and an operating member extending therethrough, a snap mechanism operable by and controlled by said operating member disposed inside of the housing, a drum type switch, a driven member connected to said switch and a driving member connected to said snap mechanism, said driven member being spring biased to a contact opening position, means connecting said driving and driven members comprising a clutch and means operable upon overload in a circuit being controlled by said switch to open said clutch and disengage said driving and driven members, and auxiliary means to cause re-engagement of said clutch during a period of overload.

6. In a switch mechanism of the class described comprising a housing, a pair of supporting members carried by the base of the housing, said supporting members being spaced apart to provide a channel therebetween and stationary contacts carried thereby on opposite sides of said channel, a movable contact carrying drum supported for rotational movement in said channel, contacts carried by said drum for engagement 70 with the stationary contacts, means to rotate

said drum comprising a lever disposed outside the housing and a shaft extending in sealed relation through the housing, a snap action mechanism disposed inside the housing connected to and operable by said lever, and means for connecting said snap mechanism to the drum comprising a driving member connected to the snap mechanism and a driven member connected to the drum, said driven and driving members being capable of independent relative movement and means interposed between the driving and driven members to effect driving relation therebetween and circuit load responsive means for connection to means between the driving and driven members to disconnect said driving and driven members.

7. In a switch mechanism of the class described comprising a housing, a pair of supporting members carried by the base of the housing, said supporting members being spaced apart to provide a channel therebetween and stationary contacts carried thereby on opposite sides of said channel, a movable contact carrying drum supported for rotational movement in said channel, contacts carried by said drum for engagement with the stationary contacts, means to rotate said drum comprising a lever disposed outside the housing and a shaft extending in sealed relation through the housing, a snap action mechanism disposed inside the housing connected to and operable by said lever, and means for connecting said snap mechanism to the drum comprising a driving member connected to the snap mechanism and movable thereby, a driven member connected to the drum, said driven and driving members being capable of independent relative movement and means interposed between the driving and driven members to effect driving relation therebetween and circuit load responsive means for connection to means between the driving and driven members to disconnect said driving and driven members and spring means biasing said drum to a contact opening position and effective upon disconnection of the driving and driven members to open the contacts.

8. In a switch mechanism of the class described comprising a housing, a pair of supporting members carried by the base of the housing, said supporting members being spaced apart to provide a channel therebetween and stationary contacts carried thereby on opposite sides of said channel, a movable contact carrying drum supported for rotational movement in said channel, contacts carried by said drum for engagement with the stationary contacts, said movable contacts being supported for movement relative to the drum and spring means biasing the contacts to an inclined position and abutment means to limit the movement thereof, means to rotate said drum comprising a lever disposed outside the housing and a shaft extending in sealed relation through the housing, a snap action mechanism disposed inside the housing connected to and operable by said lever, and means for connecting said snap mechanism to the drum comprising a driving member carried by the snap mechanism and movable thereby, a stub shaft extending from said lever and supporting one end of the drum, a driven member disposed on said stub shaft and connected to the drum, said driven and driving members being capable of independent relative movement and means on said stub shaft interposed between the driving and driven members to effect driving relation therebetween

and circuit load responsive means for connection to means between the driving and driven members to disconnect said driving and driven members and spring means biasing said drum to a contact opening position and effective upon disconnection of the driving and driven members to open the contacts.

9. An apparatus of the class described, comprising a housing, a pair of fixed contact carrying blocks secured in the housing and formed to provide a channel therebetween, a movable contact carrying drum rotatably supported in said housing between said fixed contact carrying blocks, means to rotate said drum to cause engagement and dis-engagement of the contacts comprising a driven member connected to the drum and spring means biasing said member to a contact opening position, means for operating the driven member comprising a snap action mechanism disposed in the housing at one end of said fixed contact carrying blocks, a driving member carried thereby juxtaposed to said driven member and means interposed between said driving and driven member to connect said members to each other, spring means to maintain said connection and thermally responsive means to break said connection, said biasing means adapted to open said contacts when the thermally responsive means operates.

10. An apparatus of the class described, comprising a housing, a pair of fixed contact carrying blocks secured in the housing and formed to provide a channel therebetween, a movable contact carrying drum rotatably supported in said housing between said fixed contact carrying blocks, means to rotate said drum to cause engagement and dis-engagement of the contacts comprising a driven member connected to the drum and spring means biasing said member to a contact opening position, means for operating the driven member comprising a snap action mechanism disposed in the housing at one end of said fixed contact carrying blocks, a driving member carried thereby juxtaposed to said driven member and means interposed between said driving and driven member to connect said members to each other, spring means to maintain said connection and thermally responsive means to break said connection, said biasing means adapted to open said contacts when the thermally responsive means operates, and manually operated means disposed for engagement with said connecting means for the driving and driven members movable to cause said means to be effective when the thermally responsive means has acted.

MAX LEROY JEFFREY.
